Primary Examiner—Ted Shooman**Assistant Examiner—C. Tuttle****Attorney, Agent, or Firm—John R. Flanagan****[57]****CLAIM**

The ornamental design for a lip balm dispenser holder, as shown and described.

DESCRIPTION

FIG. 1 is a perspective view of a lip balm dispenser holder, showing my new design;

FIG. 2 is a front elevational view of the holder, with a lip balm dispenser being shown in phantom;

FIG. 3 is a left side elevational view of the holder, with a lip balm dispenser being shown in phantom;

FIG. 4 is a right side elevational view of the holder, with a lip balm dispenser being shown in phantom;

FIG. 5 is a rear elevational view of the holder, with a lip balm dispenser being shown in phantom;

FIG. 6 is a top plan view of the holder; and,

FIG. 7 is a bottom plan view of the holder.

The broken line showing of the lip balm dispenser is for illustrative purposes only and forms no part of the claimed design.
